Application August 23, 1944, Serial No. 550,828

8 Claims. (CL 175—320)

1

This invention relates to certain new and useful improvements in electronic impulse counting and timing circuits.

Among the objects of our invention may be mentioned the following:

To provide a circuit of the class described utilizing gaseous discharge tubes or so-called thyratrons, which are successively ionized or fired by incoming impulses.

To provide such a counting circuit in which as each tube successively ionizes or fires, it extinguishes the preceding tube.

To provide circuits of the class described in which there is no theoretical limit to the number of tubes which may be employed for successive operation.

To provide counting apparatus of the class described which is free from the possibility of erroneous or incorrect counting and which, therefore, may be utilized in apparatus where faulty operation cannot be tolerated.

Still other objects and advantages of our invention will be apparent from the specification.

The features of novelty which we believe to be characteristic of our invention are set forth with particularity in the appended claims. Our invention itself, however, both as to its fundamental principles and as to its particular embodiments, will best be understood by reference to the specification and accompanying drawing, in which the single figure is a circuit diagram of one form of circuit in accordance with our invention.

Referring now more particularly to the drawing, we have shown a circuit particularly arranged to count by fours, but it will be understood that a smaller number of tubes may be provided if the maximum number of impulses desired to be counted is less than four. Also, more particularly, the system can be extended by adding additional stages without theoretical limit if it is desired to count more than fours.

Incoming pulses may be received upon the input terminals T1 shunted by condenser C11, the lower terminal of which may be connected to ground through resistance R11, and the common point of condenser C11 and resistance R11 may be connected to the control electrode 1g of tube 1.

The first counting tube is indicated as T1, and, as previously stated, is preferably a tube of the thyratron type, which may have cathode 1c, control electrodes 1g and 1sg, and anode 1a. The anode may be connected through current-limiting resistance R16 and through the energizing winding of relay R1 to back contact A2'b of relay 2, thence through armature A2' of relay 2

2

to back contact A3'b of relay 3, thence through blade A3' of relay 3 to back contact A4b of relay 4, and through blade A4 of relay 4 to +B.

Cathode 1c may be connected through resistance R12 to the +B supply and through resistance R13 to ground, and the control electrode 1g may be connected to cathode 1c. Cathode 1c may be connected through condenser C13 to control electrode 2g of tube T2. A connection may also be provided from cathode 1c through condenser C12 to ground and through resistances R14 and R15 to ground.

Tube T2 may be a thyratron having cathode 2c, a pair of control electrodes 2g and 2sg, and anode 2a. The cathode may be connected through resistance R22 to +B, control electrode 2g through resistance R15 to ground, and second control electrode 2sg through condenser C21 to the high potential input terminal and through resistance R21 to ground.

Anode 2a may be connected through resistance R26, the energizing winding of relay 2 to back contact A3'b and thence to +B as in the case of anode 1a, and cathode 2c may likewise be connected through condenser C22 to ground and through resistances R24 and R25 in series to ground and through capacity C23 to control electrode 3g of tube T3.

Tube T3 may be a thyratron having cathode 3c, control electrodes 3g and 3sg, and anode 3a. Cathode 3c may be connected through resistor R32 to +B, through resistances R33 condenser C32 in parallel to ground, through resistances R34 and R35 in series to ground, and through condenser C33 to control electrode 4g of tube T4. Anode 3a may be connected through resistance R36 and energizing winding of relay R3 to back contact A4a of relay R4 and to +B as before.

Tube T4 may likewise be a thyratron having cathode 4c, control electrodes 4g and 4sg, and anode 4a. The cathode may be connected through resistance R42 to +B and through resistance R43 to ground. Control electrode 4g may be connected through resistance R35 to ground and control electrode 4sg may be connected through condenser C41 to the high potential input terminal and through resistance R41 to ground. Anode 4a may be connected through resistance R46 and actuating winding of relay 4 to the +B side of the winding of relay 3 and thus to +B in the same manner as relay 3.

Relay 1 may comprise armature A1 normally biased to back contact A1b, but movable to front contact A1f when the relay is energized. Front

contact A_{1f} may be connected to output terminal T_1 .

Relay Re_2 controls armature A_2 and A_2' , and these armatures are biased against back contacts A_{2b} and $A_{2'b}$ respectively and closed against front contacts A_{2f} and $A_{2'f}$ by the energizing of relay Re_2 . Closure of relay Re_2 connects the armature A_2 to output terminal T_2 .

Relay Re_3 may have armatures A_3 and A_3' , and these are normally biased against back contacts A_{3b} and $A_{3'b}$, and are moved to front contacts A_{3f} and $A_{3'f}$ by the closure of relay Re_3 . Closure of relay Re_3 connects armature A_3 to output terminal T_3 and armature A_1 may be connected to back contact A_{2b} , armature A_2 to back contact A_{3b} , and armature A_3 to the source of $+A$ voltage.

In the present instance, only three output terminals, T_1 , T_2 , and T_3 , are shown, since in the present instance it is desired to provide only three controls; tube T_4 , which operates in response to the fourth received impulse, not controlling any external apparatus. It will be understood, however, that should this be desired, an output terminal T_0 may be provided, connected to contact A_{4b} , to be energized by the operation of relay 4.

The operation of the circuit may now be understood by reference to the following description: Tubes T_1 , T_2 , T_3 , and T_4 are preferably of the gas-filled variety, such as type 2050, and having characteristics such that if either or both control grids are maintained at a sufficient negative potential with respect to cathode, ionization of the tube cannot occur. However, if the voltages of both control electrodes are not sufficiently negative, ionization will occur and plate current will flow without grid control until the plate circuit is interrupted.

All cathodes, $1c$, $2c$, $3c$, and $4c$, are maintained at the same positive potential (in the absence of ionization in any tube) by voltage dividers consisting of resistances R_{12} and R_{13} for cathode $1c$, resistances R_{22} and R_{23} for cathode $2c$, resistances R_{32} and R_{33} for cathode $3c$, and resistances R_{42} and R_{43} for cathode $4c$. When any tube ionizes, the flow of plate current causes the potential of the cathode to rise in a positive direction. The voltage dividers R_{14} and 15 , R_{24} and 25 , and R_{34} and 35 , are so arranged that the voltage at the midpoint when a tube (except the last) is ionized is the same as the voltage at the cathode of the following tube when the said following tube is not ionized.

Thus the voltage difference between any of the control electrodes $2a$, $3g$, and $4g$ and the respective cathode $2c$, $3c$, and $4c$ is either zero or some negative value, depending on whether the previous tube is ionized. The voltage difference between the control electrode $1g$ and its cathode $1c$ is always zero, since, as will be observed, these two are directly connected.

The second control electrode, $1g$, $2sg$, $3sg$, and $4sg$, of each tube is connected to the source of positive voltage pulse through the respective condensers C_{11} , C_{21} , C_{31} , and C_{41} , and each is maintained at a normal potential more negative than its respective cathode, but returning to $+B$ through resistance R_{11} , R_{21} , R_{31} , and R_{41} respectively to ground, to which $-B$ is connected. The amplitude of the input voltage pulses may be at least sufficient to momentarily raise the second control electrode, $1g$, $2sg$, $3sg$, and $4sg$, to a potential equal to the normal cathode potential.

When a pulse is applied to the input terminals T_1 , all of the second control electrodes are momentarily raised to the potential of their respective cathodes. First grids $2g$, $3g$, and $4g$ are at a negative potential with respect to their respective cathodes, and so tubes T_2 , T_3 , and T_4 are prevented from ionizing on the first impulse.

The first tube T_1 has no first grid bias and, therefore, ionizes, and the plate current energizes relay 1, closing armature A_1 against front contact A_{1f} and thereby applying potential to terminal T_1 , which may be used to control a circuit which it is desired to have respond to the first impulse.

When the first tube ionizes, the voltage between the grid $2g$ and the cathode of the second tube T_2 is reduced to zero, the next impulse raises all second control electrodes, $1g$, $2sg$, $3sg$, and $4sg$, to cathode potential, and tube T_2 then ionizes. Tubes T_3 and T_4 , however, will not ionize on the second impulse because their grids $3g$ and $4g$ still have a negative bias sufficient to prevent ionization.

The flow of plate current in tube 2 energizes relay Re_2 and connects armature A_2 against front contact A_{2f} , thereby applying voltage to terminal T_2 . Simultaneously the plate current of tube T_1 is interrupted by opening of the plate circuit at back contact $A_{2'b}$, but relay Re_2 and tube T_1 , therefore, deionizes, deenergizing relay Re_1 and interrupting the circuit to terminal T_1 at front contact A_{1f} of relay Re_1 .

The operation proceeds similarly for the third impulse, which causes tube T_3 to ionize and thereby prepares tube T_4 to be ionized on the fourth impulse. The flow of plate current in tube T_3 energizes relay Re_3 to close armature A_3 against front contact A_{3f} , connecting T_3 to $+A$ and also interrupting the flow of plate current through relay 2 at back contact $A_{3'b}$, thereby deionizing tube T_2 and causing opening of the control circuit from terminal T_2 at front contact A_{2f} .

Reception of the fourth impulse causes ionization of tube T_4 , thereby energizing relay Re_4 and closing armature A_4 against front contact A_{4f} and interrupting the plate circuit of all of the tubes at back contact $A_{4'b}$. This causes deionization of tubes T_3 and T_4 and restores the apparatus to initial position ready to respond to the first impulse of a second counting cycle.

When any tube in the series is caused to ionize, the current in the cathode resistor does not reach its full value instantaneously, but rises exponentially at a rate determined by the relay inductance and plate circuit resistance and, therefore, a length of time T elapses between the time when ionization begins in any tube and the time when the next successive tube is capable of being ionized by the next impulse, and this limits the rapidity with which impulses may be counted. For this reason condensers C_{13} , C_{23} , and C_{33} are provided in parallel with resistances R_{14} , R_{24} , and R_{34} , respectively.

Provision of these capacities gives a leading phase characteristic to the circuits and partly compensates for the inductive lag and permits the voltage of the following grid to rise to its final value considerably more rapidly than it would were these condensers not provided, and, therefore, permits the apparatus to count impulses separated by periods of time considerably less than would otherwise be possible.

For the purpose of completing this disclosure, but not in limitation, the following table of values is given:

Resistance	Ohms	Resistance	Ohms
R11	100,000	R26	6,800
R12	33,000	R31	100,000
R13	2,700	R32	33,000
R14	180,000	R33	2,700
R15	100,000	R34	180,000
R16	6,800	R35	100,000
R21	100,000	R36	6,800
R22	33,000	R41	100,000
R23	2,700	R42	33,000
R24	180,000	R43	2,700
R25	100,000	R46	6,800

While we have shown and described certain preferred embodiments of our invention, it will be understood that modifications and changes may be made without departing from the spirit and scope thereof, as will be clear to those skilled in the art.

In this application we have explained the principles of our invention and the best mode in which we have contemplated applying those principles, so as to distinguish our invention from other inventions; and we have particularly pointed out and distinctly claimed the part, improvement, or combination which we claim as our invention or discovery.

We claim:

1. In a counting circuit, in combination, a plurality of thyratrons, each having a cathode, an anode, and a pair of control electrodes, a relay in the space current circuit of each of said thyratrons, contacts actuated by said relays to set up successive circuits upon ionization of each tube, and means for applying a voltage drop in the space current circuit of each of said thyratrons to one control electrode of the successive tube to prepare each successive tube for operation, and means for applying impulses to be counted to the other control electrodes of all said thyratrons.

2. In a counting circuit, in combination, a plurality of thyratrons, each having a cathode, an anode, and a pair of control electrodes, a relay in the space current circuit of each of said thyratrons, contacts actuated by said relays to set up successive circuits upon ionization of each tube, a resistor in the cathode circuit of each of said thyratrons, and means for applying the voltage drop in said resistor to one control electrode of the successive tube to prepare each successive tube for operation, and means for applying impulses to be counted to the other control electrodes of all said thyratrons.

3. In a counting circuit, in combination, a plurality of thyratrons, each having a cathode, an anode, and a pair of control electrodes, a relay in the space current circuit of each of said thyratrons, contacts actuated by said relays to set up successive circuits upon ionization of each tube, and to open the space current circuit of the previous tube, and means for applying a voltage drop in the space current circuit of each of said thyratrons to one control electrode of the successive tube to prepare each successive tube for operation, and means for applying impulses to be

counted to the other control electrodes of all said thyratrons.

4. In a counting circuit, in combination, a plurality of thyratrons, each having a cathode, an anode, and a pair of control electrodes, a relay in the space current circuit of each of said thyratrons, contacts actuated by said relays to set up successive circuits upon ionization of each tube, and to open the space current circuit of the previous tube, the last tube of the series opening its own space current path, and means for applying a voltage drop in the space current circuit of each of said thyratrons to one control electrode of the successive tube to prepare each successive tube for operation, and means for applying impulses to be counted to the other control electrodes of all said thyratrons.

5. In a counting circuit, in combination, a plurality of thyratrons, each having a cathode, an anode, and a pair of control electrodes, a relay in the space current circuit of each of said thyratrons, contacts actuated by said relays to set up successive circuits upon ionization of each tube, means for applying a voltage drop in the space current circuit of each of said thyratrons to one control electrode of the successive tube to prepare each successive tube for operation, the corresponding control electrodes of each tube except the first having the same operating potential in the absence of ionization of any tube, and means for applying impulses to be counted to the other control electrodes of all said thyratrons.

6. In a counting circuit, in combination, a plurality of thyratrons, each having a cathode, an anode, and a pair of control electrodes, a relay in the space current circuit of each of said thyratrons, contacts actuated by said relays to set up successive circuits upon ionization of each tube, and means for applying a voltage drop in the space current circuit of each of said thyratrons to one control electrode of the successive tube to prepare each successive tube for operation, the potential difference between corresponding control electrodes and the cathode of the various tubes except the first being either zero or a negative value, depending on whether the previous tube is ionized, and means for applying impulses to be counted to the other control electrodes of all said thyratrons.

7. In a counting circuit, in combination, a plurality of thyratrons, each having a cathode, an anode, and a pair of control electrodes, a relay in the space current circuit of each of said thyratrons, contacts actuated by said relays to set up successive circuits upon ionization of each tube, and means for applying a voltage drop in the space current circuit of each of said thyratrons to one control electrode of the successive tube to prepare each successive tube for operation, each of said tubes except the last including in its control circuit a voltage divider arranged so that the voltage at the midpoint thereof when a tube is ionized is the same as the voltage at the cathode of the following tube when said following tube is ionized, and means for applying impulses to be counted to the other control electrodes of all said thyratrons.

8. In a counting circuit, in combination, a plurality of thyratrons, each having a cathode, an anode, and a pair of control electrodes, a relay in the space current circuit of each of said thyratrons, contacts actuated by said relays to set up successive circuits upon ionization of each tube, means for applying a voltage drop in the space current circuit of each of said thyratrons to one

control electrode of the successive tube to prepare each successive tube for operation, and a condenser in shunt with a portion of said voltage divider to provide a leading phase characteristic partly compensating for inductive lag in the circuit, and means for applying impulses to be counted to the other control electrodes of all said thyratrons.
